UNITED STATES PATENT OFFICE.

ALEXANDER B. WAY, OF LYNN, MASSACHUSETTS, ASSIGNOR TO LEWIS A. WAY, OF PITTSBURGH, PENNSYLVANIA.

METHOD OF TREATING HYDROCARBONS.

No Drawing.

Application filed March 19, 1924. Serial No. 700,381.

This invention relates to a method of treating hydrocarbons to demulsify the same and generally improve their qualities.

This method constituting the subject matter of the present invention may be employed in the treatment of hydrocarbons of numerous grades and of varying condition.

Oils of the grades used in oil burners and the like are especially subject to separation of their heavier components when permitted to stand in containers for storage or transportation, or in service tanks for supplying the fuel to the point of their combustion. This separation usually results in the collection of a slime, comprising heavy sludge, separated carbon, or other relatively dense substances, at the bottom of the tank or container. Such condition results in the loss of combustible material, and also in the fouling of cleaning screens and meters during utilization of the oils.

Any oil when stored or transported tends to receive and form an emulsion with water, which may leak into the tank or container, be absorbed from the moisture of the atmosphere, or enter the body of the oil at some preliminary stage during its production or treatment. Such emulsion tends to prevent the redissolution of heavier separated components of the oil, because of the formation of the minute globules of the emulsion. The surface tension of such globules prevents their breaking up to release the oil, and prevents redissolution of the separated heavier components of the oil.

One object of the present invention is therefore to provide a method of treating a hydrocarbon oil which reduces the surface tension of the globules of any emulsion present, and permits both the removal of the water of such emulsion and the redissolution of the separated heavier components of the oil.

Another object of the invention is to provide a method which operates to produce the above effect without involving such application of heat as to raise the temperature of the oil to a point at which the loss of any portion or components thereof takes place through distillation or coking.

Certain grades of oil, moreover, which

are incapable of combustion in burners or the like because of their thickness and lack of fluidity, may be rendered fluid and usable by treatment according to the method of the present invention. Likewise the heaviest tars may be broken up by treatment according to such method, and rendered sufficiently fluid to permit their removal from storage tanks and containers.

Lubricating oils may be rendered more efficient by treatment according to the method of the invention. Such treatment diminishes its viscosity without a corresponding decrease in density. Smaller quantities of an oil of given viscosity may therefore be employed to provide an adequate lubricating film, and the life of the lubricant is increased. Cylinder oil for internal combustion engines, when so treated, causes less deposit of carbon than when untreated and has less tendency to thicken and gum in cold weather than untreated oil of equal lubricating value but greater viscosity.

A specific formula for the material utilized in the treatment may be given as follows: Naphthalene ($C_{10}H_8$) by volume 95%; nitro-benzol ($C_6H_5NO_2$) by volume 4.5%.

In this formula the naphthalene, which is a crystalline hydrocarbon, absorbs the nitro-benzol, which is in the condition of a heavy oil, and the more volatile alizarin, to produce a single and apparently homogeneous material.

Such solid mixture may be desirably in divided form. To secure such form the naphthalene is preferably cut and screened, and a portion thereof further granulated prior to the incorporation of the nitro-benzol. In practice it is found convenient to use approximately seventy-five parts of the flake naphthalene to twenty-five parts of the granulated naphthalene.

If the mixture is to be employed to produce the breaking up and redissolution of a heavy slime, such as sludge or tar, such sediment is first covered with a relatively large volume of oil in fluid condition, and the treating mixture added to this initial hydrocarbon mixture. With such initial hydrocarbon the treating material is preferably added in a quantity of from 0.5 pounds to 1.5 pounds to each 500 gallons

2
of the mixture of sediment and oil. This mass, consisting of the sediment, oil, and treating mixture is subjected to gentle heating, and maintained at a temperature of from one hundred degrees Fahrenheit to two hundred degrees Fahrenheit for a period of from one hour to eighteen hours. The duration of the treatment depends upon the nature of the initial hydrocarbon to be treated, the rate of dispersion of the treating material through this initial hydrocarbon, and the length of time required to exhaust the treating material.

When the treating material has been exhausted, another charge may be added, and the gentle heating continued until exhaustion of such second charge. In certain instances a third treatment may prove desirable.

20 If an oil having no appreciable quantity of sediment associated therewith is to be treated simply to demulsify such oil and to generally improve its qualities, the general nature of the treatment is identical with 25 that given above. In such case, however, a single charge of the mixture is generally sufficient to produce the desired result. The quantity of the mixture with relation to the volume of the initial hydrocarbon to be 30 treated may also be greatly reduced.

In either of the cases noted above, water separated by the demulsification of the oil is drawn off prior to use of the oil.

If an oil is to be treated to generally improve its qualities, without the necessity for demulsification of such oil, the quantity of the mixture employed may be still further reduced.

Not only the quantity of the mixture employed, but also the relative proportions of its ingredients, may be desirably varied in accordance with the work to be done. Thus for the breaking up of heavy tars, to increase their fluidity, one pound of the mixture is 45 preferably added for each two hundred and fifty to three hundred gallons of the tar; and the nitro-benzol content may be increased to as much as ten per cent by volume of the entire mixture.

50 To consider the different ingredients of the mixture, the nitro-benzol (or its equivalent) performs the chief active function in breaking down the globules of an emulsion, and diminishing the viscosity of a body of 55 a hydrocarbon. The naphthalene (or its equivalent) assists to some extent in performing these functions, and also serves as a convenient carrier for the other ingredients, whereby they may be conveniently 60 stored and transported and may be distributed through the hydrocarbon body to be treated.

As to equivalent, or substitute, substances in the mixture, anthracene ($C_{14}H_{10}$) which 5 is a crystalline hydrocarbon resembling

naphthalene in its physical properties, may be used to take the place of the latter.

As an equivalent for the nitro-benzol, another nitro compound of the aromatic series of hydrocarbons, such as nitro-toluol ($C_6H_4CH_3NO_2$) may be employed. 70

Whereas these alternative substances serve to impart the desired useful properties to the mixture, the substances included in the formula given above are preferred because 75 of the fact that they are in more common use or because of the fact that they are more readily produced on a commercial scale.

It is also possible to employ nitro-naphthalene or nitro-anthracene, which are themselves nitro compounds of hydrocarbons derived from the same source as the aromatic series of hydrocarbons, mainly from the distillation of coal. These compounds may either one be used with either the nitro-benzol or nitro-toluol of the formula. 80

Favorable, though less satisfactory, results have been obtained by using either nitro-naphthalene or nitro-anthracene alone.

Benzaldehyde may be used to replace the 90 nitro-benzol or nitro-toluol, though not with wholly satisfactory results. Oil of bitter almonds (mirbane) may also be similarly used. It should be noted that this oil, though an essential oil of vegetable origin, 95 closely resembles nitro-benzol both in chemical structure and in characteristics.

It will be seen from the above that the particular substances noted in the formula, as well as the relative proportions of such 100 substances, may be varied within the scope of the disclosure and the appended claims without departing from the spirit of the present invention.

It is also to be noted that all substances 105 noted are organic compounds. When used for the treatment of hydrocarbons, they therefore leave no incombustible residue as do inorganic treating materials such as aluminum chloride, and the like. 110

What I claim is:

1. The process of treating hydrocarbons to demulsify the same and increase their fluidity which consists in subjecting the initial hydrocarbon to the action of a mixture of 115 naphthalene and nitro-benzol in solid state and divided form.

2. The process of treating hydrocarbons to demulsify the same and increase their fluidity which consists in subjecting the initial hydrocarbon to the action of a mixture of naphthalene and nitro-benzol in solid state and divided form, and subjecting the 120 mass to the action of heat.

3. The process of treating hydrocarbons 125 to demulsify the same and increase their fluidity which consists in subjecting the initial hydrocarbon to the action of a mixture of naphthalene and nitro-benzol in solid state and divided form, and subjecting the

- mass to the action of heat at a temperature not in excess of two hundred degrees Fahrenheit.
4. The process of treating hydrocarbon oils to demulsify the same and increase their fluidity which consists in subjecting the initial hydrocarbon to the action of a mixture including a crystalline aromatic hydrocarbon and nitro-benzol, said mixture being in solid state and divided form.
5. The process of treating hydrocarbon oils to demulsify the same and increase their fluidity which consists in subjecting the initial hydrocarbon to the action of a mixture including a crystalline aromatic hydrocarbon and nitro-benzol, and subjecting the mass to the action of heat at a temperature no higher than two hundred degrees Fahrenheit.
6. The process of treating hydrocarbons to demulsify the same and increase their fluidity which consists in subjecting the initial hydrocarbon to the action of an added mixture including a crystalline aromatic hydrocarbon serving as a carrier, and a nitrated hydrocarbon having no more than moderate explosive properties absorbed by said crystalline hydrocarbon.
7. The process of treating hydrocarbons to demulsify the same and increase their fluidity which consists in subjecting the initial hydrocarbon to the action of an added mixture including naphthalene as a carrier, and a nitrated hydrocarbon having no more than moderate explosive properties absorbed by said naphthalene.
8. The process of treating hydrocarbons to demulsify the same and increase their fluidity, which consists in subjecting the initial hydrocarbon to the action of an added mixture including a crystalline aromatic hydrocarbon serving as a carrier, and a nitrated hydrocarbon having no more than moderate explosive properties absorbed by said crystalline hydrocarbon, said mixture being in divided form.
9. The process of treating hydrocarbons to demulsify the same and increase their fluidity, which consists in subjecting the initial hydrocarbon to the action of an added mixture including naphthalene as a carrier, and a nitro compound of a hydrocarbon having no more than moderate explosive properties absorbed by said naphthalene, said mixture being in divided form.
10. The process of treating hydrocarbons to demulsify the same and increase their fluidity, which consists in subjecting the initial hydrocarbon to the action of an added mixture including a crystalline aromatic hydrocarbon serving as a carrier, and a nitrated hydrocarbon having no more than moderate explosive properties absorbed by said crystalline hydrocarbon; and subjecting the mass to the effect of heat at a temperature no higher than two hundred degrees Fahrenheit.
11. The process of treating hydrocarbons to demulsify the same and increase their fluidity, which consists in subjecting the initial hydrocarbon to the action of an added mixture including naphthalene as a carrier, and a nitrated hydrocarbon having no more than moderate explosive properties absorbed by said naphthalene, and subjecting the mass to the effect of heat at a temperature no higher than two hundred degrees Fahrenheit.
12. The process of treating hydrocarbons to demulsify the same and increase their fluidity, which consists in subjecting the initial hydrocarbon to the action of an added mixture including a crystalline aromatic hydrocarbon serving as a carrier, and a nitrated hydrocarbon having no more than moderate explosive properties, said mixture being in divided form; and subjecting the mass to the effect of heat at a temperature no higher than two hundred degrees Fahrenheit.
13. The process of treating hydrocarbons to demulsify the same and increase their fluidity, which consists in subjecting the initial hydrocarbon to the action of an added mixture including naphthalene as a carrier, and a nitrated hydrocarbon having no more than moderate explosive properties absorbed by said naphthalene, said mixture being in divided form; and subjecting the mass to the effect of heat at a temperature no higher than two hundred degrees Fahrenheit.

In witness whereof, I hereunto set my hand.

ALEXANDER B. WAY.
